CLAMP FOR CURTAIN STRETCHERS

Werner H. Bothe, Kenosha, Wis., assignor to
Worldsbest Industries, Inc., Cudahy, Wis., a
corporation of Wisconsin

Application September 4, 1947, Serial No. 772,176

4 Claims. (Cl. 287—54)

1

The invention relates to curtain stretchers and more particularly to a fitting for clamping two angularly disposed frame members of a stretcher together. Fittings of this kind are used for clamping the ends of the vertically adjustable bottom bar to the end bars of the stretcher frame and the horizontally adjustable bar to the top bar of the stretcher frame.

One object of the invention is to provide a fitting of simple construction for clamping angularly disposed frame members of the stretcher together which provides a large bearing contact between the clamping member and the bar it engages.

A further object of the invention is to provide a clamping device of the type above described in which the metal clamping head or jaw has a self-compensating or leveling action relative to its anchorage so that it will readily accommodate any irregularities in the surface of the bar it engages.

The invention further consists in the several features hereinafter set forth and more particularly defined by claims at the conclusion hereof.

In the drawings:

Fig. 1 is a front elevation view of a curtain stretcher, parts of which are equipped with a fitting embodying the invention;

Fig. 2 is an enlarged front elevation view of the fitting;

Fig. 3 is a detailed vertical sectional view taken on the line 3—3 of Fig. 2;

Fig. 4 is a view similar to Fig. 2, with parts broken away, showing the self-compensating action of the fitting embodying the invention.

Curtain stretchers embody top and bottom bars 5, side or end 6, a vertical center bar 7, and a vertical adjustably mounted bar 8 secured together by various fittings to form a stretching frame, the top and bottom bars, one of the end bars, and the bar 8 usually being provided with pins 9 on which portions of the damp curtains or other fabrics are impaled to stretch the fabric and hold it in this condition until dried.

The present invention is directed to a fitting which clamps the upper end of bar 8 with the top bar and which clamps the ends of the bottom bar to the end bars 6.

Referring to Figs. 2 to 4, inclusive, the new fitting includes a base or anchoring member 10 secured by rivets 11 to one of the frame bars, such as to the upper end of the bar 8 or the ends of the bottom bar 5, said member having an angled end 12 between which and the end of the carrying bar 8 or 5 another frame bar such as the top bar

2

5 or either side bar 7 is slidably mounted in right angled relation, and so that one side of said last named bar abuts the end of the other frame bar. To secure these bars in abutting clamped relation, 5 a clamping bolt 13 of the carriage type having squared portion 14 adjacent its head is loosely mounted in a square hole 15 in the angled end 12, so that it cannot rotate relative thereto, and its threaded shank 16 carries a clamping nut 17 such as a wing nut. Loosely mounted on the shank of said bolt 13 so that it may swivel or cant relative thereto is a U-shaped clamping head or jaw member 18 having a hole 19 in its transverse portion through which said bolt passes loosely and having its legs provided with angled feet 20 to engage the bar to be clamped over a considerable area as compared to the usual C-type clamps that have been heretofore used. A spring 21 interposed between the angled end 12 and the head 18 holds the bolt 13 in assembled relation with its anchoring member and the head 18 against the adjusting screw.

With this construction when the two bars to be clamped are assembled together in right angled relationship and the wing nut 17 is turned to move the head 18 inwardly relative to the shank 13 and the bar such as the bar 5 or bars 7, the head 18 is brought into clamping engagement with said bar and clamps the same between it and the end of 20 the other bar at spaced points and over a relatively large clamping area, and even if the side of the bar with which the head engages be nicked, dented, or uneven as indicated at 22 in Fig. 4, the clamp will still engage the bar with both of its feet 20 since the loose connection of said head with the bolt permits said head to cant or tip relative to the shank of the bolt and also the loose connection of the bolt at 14 with the part 12 permits the bolt to tip or cant slightly.

40 I desire it to be understood that this invention is not to be limited to any particular form or arrangement of parts except in so far as such limitations are included in the claims.

What I claim as my invention is:

45 1. In a curtain stretcher having frame bars extending at angles to each other, one of said bars abutting an end of the other bar, a fitting for securing said bars in abutting clamped relation comprising a member anchored to one of 50 said bars and having an end in spaced relation thereto, a threaded clamping bolt carried by said end of said member, a clamping head loosely mounted on the shank of said bolt, and engageable at spaced points with the other bar, and a 55 clamping nut mounted on said bolt and engage-

able with said head to move it to a clamping position.

2. In a curtain stretcher having frame bars extending at angles to each other, one of said bars abutting an end of the other bar, a fitting for securing said bars in abutting clamped relation comprising a member anchored to one of said bars and having an end in spaced relation thereto, a threaded clamping bolt mounted against rotation in said end of said member, a clamping head loosely mounted on the shank of said bolt and engageable at spaced points with the other bar, a clamping nut mounted on said bolt and engageable with said head for moving the same to a clamping position, and a spring interposed between said end and said head to maintain contact of said head with said nut and hold said bolt in assembled relation with said end.

3. In a curtain stretcher having frame bars extending at angles to each other, one of said bars abutting an end of the other bar, a fitting for securing said bars in abutting clamped relation comprising a member anchored to one of

said bars, a threaded clamping bolt carried by said member in spaced relation to its carrying bar, a U-shaped clamping member having angled feet engageable at spaced points with said abutting bar, and a clamping nut mounted on said bolt and engageable with said clamping member for moving the same to a clamping position.

4. In a curtain stretcher having frame bars extending at angles to each other, one of said bars abutting an end of the other bar, a fitting for securing said bars in abutting clamped relation comprising a member anchored to one of said bars, a threaded clamping bolt having a non-rotatable mounting in said member in spaced relation to its carrying bar, a U-shaped clamping member slidably mounted on said bolt and engageable with the abutting bar, a clamping nut mounted on said bolt and engageable with said clamping member for moving the same to a clamping position, and a spring engageable with said clamping member to hold the same against said nut.

WERNER H. BOTHE.
